UNITED STATES PATENT OFFICE.

LUDWIG B. URI, OF SEATTLE, WASHINGTON.

TIME-CONTROLLED ACTUATING MECHANISM.

1,261,071.

Specification of Letters Patent.

Patented Apr. 2, 1918.

Application filed July 23, 1917. Serial No. 182,188.

To all whom it may concern:

Be it known that I, LUDWIG B. URI, a citizen of the United States, and resident of the city of Seattle, county of King, and State of Washington, have invented certain new and useful Improvements in Time-Controlled Actuating Mechanism, of which the following is a specification.

My invention relates to time controlled devices for starting mechanisms and comprises the novel parts and combinations of parts which will be hereinafter described and then particularly defined by the claims.

The object of my invention is to provide means whereby an alarm clock, or like time controlled device, may be readily applied to, and removed from, objects which it is desired to start in operation at predetermined time.

In the accompanying drawings I have shown my device embodied in the form of construction which is now most preferred by me.

Figure 1 is a top plan view of a phonograph table, showing my device applied thereto.

Fig. 2 shows, in enlarged scale, the application of my device to the same mechanism but showing the parts in different position.

Fig. 3 is a perspective, showing parts broken away, of my device as viewed from beneath.

Fig. 4 is a perspective of the plate which is attached to the stationary table of a phonograph and to which my device is applied and by which the device is rendered easily applicable to and removable from said mechanisms.

I have herein shown my device as applied to a phonograph for starting the same. This particular mechanism has been chosen for purposes of illustration, but without any thought of limiting the application of the device to such mechanism. Its applicability to other mechanisms will be readily understood.

In the drawings 1 represents the table or frame upon which the turntable 10 of a phonograph is mounted. As the means for determining the time of starting of the device I employ an alarm clock, the same being herein indicated by the frame work 2.

This frame work, or casing, contains any suitable alarm clock mechanism. It is shown as provided with a base 20 and this base is provided with means whereby the

clock may be properly placed upon the mechanism to be controlled, in order to secure exact registry therewith. The means herein illustrated for securing this result consists in providing the base of the clock with projecting pins 21 and in providing the plate 22, which is adapted to be secured to the table, or other portion of the device to be controlled thereby, as by screws passing through holes 24, and additionally, if desired, by means of prongs 25 which may enter the surface of said table. This plate is provided with holes, as 23, so placed as to receive the pins or projections 21 carried by the base of the clock. In this manner, the proper position for the clock is secured so that it may be easily applied and removed with certainty that it will be in exactly the right position.

The shaft 3, shown in Fig. 3, is the shaft to which the inner end of the alarm spring is secured. This shaft has secured thereto an actuating member, which member is herein shown as arm 4. The character of this actuating member will depend upon the exact construction of the means employed for connecting said alarm mechanism with the mechanism which is to be started or controlled by my device. The arm herein shown is illustrated and described simply as typical of a connecting mechanism which may be employed to actuate the device to be controlled.

The arm 4, or its equivalent mechanism, may be connected with a device to be controlled through the medium of a second lever 5, which is pivoted at 50 in any suitable manner from the base of the clock. It is herein shown as being pivoted upon a bracket arm 51 which projects inward slightly above the lowermost level of the base. The base of the clock is also provided with an opening 55 through which the arm 5 projects.

While the arm 5 employed may be directly connected with the mechanism to be controlled, it is in many cases preferable to employ an intermediary member. I have illustrated such a member, the same consisting of the links or arms 6, which are pivotally connected with the outer end of the arm 5. I also prefer to employ a spring engaging these two parts and acting in such manner as to impel the swinging of the arms 6 in the same direction as that in which the arm 5 is impelled by the action

of the alarm spring, when the latter is released.

I have shown the links 6 as consisting of two bars which are pivoted at opposite sides 5 of the arm 5 and the spring 7 as being a flat bar fixedly secured to the outer ends of the links 6 and having its inner end engaging with a shoulder 52 carried by the outer end of the arm 5. When the arm or links 10 6 are swung inward, or into the position shown in Fig. 1 and by dotted lines in Fig. 2, the spring 7 is bent and acts to urge the arm, composed of the links 6, outwardly.

I prefer to provide the outer end of the 15 arm composed of the links 6, with a member 8, of some frictional material, such as rubber, so that it will have a good frictional grip upon the member against which it is placed. As herein illustrated, this member 20 consists of a turntable 10 of a phonograph or graphophone. When the device is released the rubber tip serves to better prevent slipping upon the periphery of the turntable. When released, the arm 5 is given 25 a prompt swing which serves to swing the turntable. Up to this time the engagement of the device with the turntable acts in the same manner as a detent, to prevent starting of the turntable. If desired, the engagement 30 of the arm 6 with the turntable, or with the equivalent member of any other device to which the same is applied, may be made positive by the use of notches, or other means for securing positive engagement. Such variation is, however, considered 35 as an equivalent of the use of the rubber tip 8.

What I claim as my invention is:

1. A time controlled starting device comprising a vertically disposed alarm clock, a vertically disposed arm secured to the alarm mechanism thereof, a horizontal lever pivoted intermediate its ends for horizontal swinging movement and having engagement

at one end with the vertical lever by which 45 it is moved when the alarm mechanism is released, an arm pivoted at one of its ends to the opposite end of the horizontally swinging lever; a disk engaging element at the free end of said arm and a spring tending 50 to swing said arm bodily about its pivot in the direction of movement of the horizontally swinging lever.

2. A time controlled starting device comprising an alarm clock, a swingingly mounted member, connections between said member and the alarm clock for swinging said member from the alarm mechanism of the clock when the latter is released, an arm pivoted to the swinging end of said member 60 for movement in the direction of movement of said member, and a spring engaging said member and said arm in such manner as to be placed under tension when the arm is moved in a direction reverse to the direction 65 of movement of said member.

3. A time controlled starting device comprising an alarm clock, a swingingly mounted member, connections between said member and the alarm clock for swinging said 70 member from the alarm mechanism of the clock when the latter is released, an arm pivoted to the swinging end of said member for movement in the direction of movement of said member, and provided at its free 75 end with means for engaging a part to be controlled, a flat spring one end of which is fixed to said arm and a shoulder carried by the member over which the other end of said spring travels when the arm is moved out of alignment with the member, said shoulder being of such shape as to flex the spring by such movement and said spring tending to move the arm into longitudinal alignment with the member.

Signed at Seattle, Washington, this 17th day of July, 1917.

LUDWIG B. UHL.
